UNITED STATES PATENT OFFICE.

HERMAN JAWORSKI, OF NEW HAVEN, CONNECTICUT, ASSIGNOR TO
SARGENT & CO., OF SAME PLACE.

DESIGN FOR BUTT-HINGES.

SPECIFICATION forming part of Design No. 11,634, dated February 3, 1880.
Application filed December 31, 1879. Term of patent 14 years.

To all whom it may concern:

Be it known that I, HERMAN JAWORSKI, of New Haven, in the county of New Haven and State of Connecticut, have invented a new Design for Butt-Hinge; and I do hereby declare the following, when taken in connection with the accompanying drawing, and the letters of reference marked thereon, to be a full, clear, and exact description of the same, and which 5
10 said drawing constitutes part of this specification, and represents a face view.

This invention relates to a design for the ornamentation of the leaves of butt-hinges; and it consists in the ornamentation, as shown 15
15 in the accompanying illustration.

On the face of the hinge, around the edge, is a plain double border with a broken bead inside. Diagonally across one corner is a bead, forming a diagonal section, filled by small 20
25 squares, and from that diagonal bead around

the edge is a series of points projecting inward across the panel, of which the said points form the border, and near the top and bottom is a bar, and at one side a segmental-shaped figure projects onto the face of the panel, and form the opposite side a branch springs from the center and turns upward and downward. This ornamentation on the face of the panel—that is, within the border—may be changed or dispensed with. 25
30

I claim—

The design for butt-hinge, consisting of the diagonal bead, forming a triangular section at one end, with a border of points around the panel, as shown in the accompanying illustration. 35

HERMAN JAWORSKI.
